STORE FRONT AND AWNING ASSEMBLY
DEVICE

Errol P. D'Azzo, New York, N. Y.

Application July 30, 1948, Serial No. 41,442

13 Claims. (Cl. 160—22)

1

This invention relates to awning boxes.

The invention aims to provide an improved awning box, of substantially water-tight construction yet capable of being expeditiously and inexpensively erected, and at the same time an awning box having a forward drop lid and manually actuatable means for positively opening the lid when the awning is to be lowered and for positively closing the lid after the awning has been raised as by rolling it up on a roller housed in the box.

A further feature of the invention is the provision of an improved hinge-mount for the drop lid, and one not including pintles or the like having to be inserted and secured in place.

A further feature of the invention is an improved sectional construction for the drop lid, such that by the use of a few standard parts, fabricable by the extrusion method, the drop lid may be given any length or width dimensions desired, according as such parts are variously combined.

Another object is to provide a construction including a tie means for the employed drop-lid sections of practicable and low-cost type, together with securing means for these parts serving to maintain their coupling under such tension that loosening of the connections between the parts is rendered impossible over the entire life of the awning box.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of an awning box pursuant to the invention, broken away at its central portion, and showing the drop-lid down.

Fig. 2 is a transverse vertical sectional view, taken at an appropriate point along the length of the awning box, as on the line 2—2 of Fig. 3.

Fig. 3 is a sectional view taken on the line 3—3 of Fig. 2.

Fig. 4 is an enlarged detailed view of the bottom portion of the upper section of the drop-lid as shown in Fig. 2.

Fig. 5 is a sectional view taken on the line 5—5 of Fig. 4.

Fig. 6 is an enlarged detailed view of the lower section of the drop-lid as shown in Fig. 2.

Fig. 7 is a sectional view taken on the line 7—7 of Fig. 6.

2

Referring to the drawing more in detail, 15 denotes the main part of an awning box adapted to be connected to a store front wall. As here illustrated this main part of the box is shown as of integral construction to provide a top 16, a rear wall 17 and a bottom 18; with this structure preferably made of light weight material such as aluminum.

Within the box may be mounted the familiar 10 roller on which the awning canvas or other material is rolled when the awning is raised. As is also familiar practice, said roller may be turned in one direction or the other, to raise or lower the awning, by means of a long rod having a 15 crank-like offset near its lower end and at its upper end having a hook to be engaged with a hook on the lower end of a stub-shaft depending from the gear-couple or the like by way of which when said stub-shaft is rotated in one direction 20 or the other a rotative movement in a corresponding direction is imparted to the roller.

In Fig. 1 such stub-shaft is indicated in dot and dash lines at 62. As will be understood, however, the present invention concerns itself 25 with the improved awning box as hereinabove first described. The present invention, therefore, may be used independently of the awning raising and lowering means installed.

The main box part 15 is shown as mounted at 30 its bottom wall 18 on a foundation 21, which may be of wood, having a forwardly downwardly sloping front portion 21A; the bottom wall 18 having its forward edge located just in back of such slope. The box part 15, as by way of its 35 rear wall 17, is suitably secured to the store wall; and the foundation 21 may be rested as indicated on top of a cornice 22 or the like overlying the entrance door and front windows of the store or shop.

The top of the drop-lid for the awning box, 40 said lid pivotally suspended from the top of the box by a hinge means later to be described in detail, is protectively embraced by an auxiliary means incorporating a channel member 23, the 45 channel of which, running longitudinally thereof, is of specially shaped cross-section as shown in Fig. 2, and a rocker member 24 for lying in said channel and of specially shaped cross-section also as shown in Fig. 2.

The channel member 23 is preferably made 50 separately from the main box part 15, and is suitably connected to and below the top 16 at the location indicated. In completing the box member 15, the sides thereof may be closed in by suitable plates as indicated at 25 and 26 in Fig. 1; and, finally, a water-tight sheet 27 of

metal or other suitable material may be applied as shown, and the same just beyond both plates 25 and 26 may be dipped downward to provide rain-water spillways.

The drop-lid is comprised of a number of parts all to extend horizontally and each of a constant cross-section, so that all of them may be extrusions of aluminum or like material. These parts, in the assembly thereof herein shown, comprise an upper section 28, a lower section 28', a panel 29, and two like clamp-bars 30 and 31.

The rocker member 24 is shown as formed integral with the upper section 28; and also shown as formed integral with the lower section 28' is a bottom apron 32 having along its lower end a canted lip 33, so that, when the awning is extended and the drop-lid lowered as in the drawing, the awning canvas passes through a narrow passage with the lip 33 pressed down somewhat lightly thereon. The lip 33, while mainly laterally projected toward the interior of the awning box, is at the same time extended outwardly as at 34 to provide a spillway for rain-water when, with the awning retracted and wholly withdrawn into the awning box, the drop-lid is lowered.

As will be noted from Fig. 2, the main body of the section 28 is shaped to have rearwardly offset therefrom an upper longitudinal rib 36 of T-shaped cross-section, a bottom longitudinal rib 37 of L-shaped cross-section, and below the root portion of said rib 37 a downwardly extending longitudinal groove 38. Between the said two ribs is provided a C-shaped channel 40. At its portion and at its side facing the interior of the channel 40, the T-head of the rib 36 has vertical serrations 36^a, in Figs. 4 and 5; and at its side facing the interior of said chamber, the upstanding limb of the L-shaped rib 37 has similar serrations 37^a, see Fig. 4.

The main body of the section 28' is shaped to have rearwardly offset therefrom an upper longitudinal rib 41 of L-shaped cross-section, this corresponding to the rib 37, and also a lower longitudinal rib 42 of T-shaped cross-section, this corresponding to the rib 36, and, further, above the root portion of the rib 41, an upwardly extending groove 43, this groove corresponding to the groove 38. The rib 41 has serrations 41^a, see Figs. 6 and 7, as above-described in connection with the rib 37, and the rib 42 has serrations 42^a as above-described in connection with the rib 36; the section 28' having a channel 44 corresponding to the channel 40.

The drop-lid is of adequate height in substantially all installations if made up of the upper and lower sections 28 and 28', and an intervening panel 29. Said panel, it will be noted, is of standard strip cross-section, and so can be readily supplied in varying widths at low cost and without special equipment of any kind, so that when specially desired the width of the drop-lid may be made exactly as specified merely by employing a panel 29 of appropriate width. Said panel is directly coupled with the sections 28 and 28' merely by pressing the longitudinal upper and lower marginal portions of the panel into the grooves 38 and 43. No special securing is here required, in view of other provisions, in part including the aforesaid serrations, and in part including means now to be described.

Said means includes the two clamp-bars 30 and 31, placed respectively in the channels 40 and 44, a tie-bar or plate 45, serrations 30^a and 31^a on the clamp-bars for inter-engagement with the serrations first-described, a suitable number

of screws 46 horizontally spaced along the drop-lid and sent through apertures in the tie-plate 45 and thence into tapped holes through the clamp-bars 30 and 31. Thus the clamp-bars may be locked in place in the channels 40 and 44, and at the same time the panel 29 may be held properly in place between the sections 28 and 28', even though the said panel may be of one or another of differing widths; in which last connection note that the apertures provided in the tie-plate 45 for the screws to be engaged with the clamp-bar 31 may be in the form of vertically elongated slots 47.

The mechanism illustrated for raising and lowering the drop-lid includes a swing-plate 48, of a width to impart an efficiently wide-spread lift to the drop-lid when the latter is to be raised. This swing-plate is hung on a shaft 49, for inward or outward swing when said shaft is fractionally rotated, as by being secured to the shaft by means of upward end extensions 50 and 51, see Figs. 2 and 3 from the swing-plate curled over and suitably secured to spaced points along the shaft as by set-screws 52. The swing-plate 48 at its bottom may carry one or more loosely revoluble rollers 53.

For coupling the swing-plate 48 and the tie-plate 45, thereby to hingeably mount the drop-lid on the shaft 49, a means is employed, also constituting a special feature of the invention, comprising an aperture 54, a screw 55 having a head 56 larger than the aperture 54, and sleeved by an expansile coil spring 57. The screw 55 is sent into a tapped hole through the tie-plate 45. Thereby a constant tension is provided for the screw 55, to prevent loosening thereof, to permit length adjustment, and to afford a finger guide.

Fixed to the shaft 49 as at 58 (Fig. 3), is a worm-gear segment 59, with which meshes a worm 60 secured as at 61 to a stub-shaft 62. The upper portion of said shaft is journalled in an aperture 63 through the bottom wall of a cage-casting 64 within which the worm 60 is housed; and the top of the shaft 62 is reduced as at 65 and there journalled in an aperture through the top wall of the cage-casting. Offset from said cage-casting is a flange 66, by way of which the cage-casting is secured to a web 67 of a bracket 68 suitably fixed at the upper interior of the awning box as by the bolts indicated at 69.

The said securing of the cage-casting 64 to the bracket 68 allows for angular adjustment of the cage-casting relative to the bracket; the cage-casting being secured to the bracket by a screw 70, passed through a washer 71 and thence through an arcuate slot 72 carried by the bracket's web 67 and thence into a tapped hole 73 in the flange 66 of the cage-casting.

The stub-shaft 62 is forwardly downwardly inclined for slight projection below the foundation 21 as shown in Fig. 2. To the lower end of said shaft is secured, as at 74, a hook 75; said hook being shown as the same as the conventional hook ordinarily carried at the bottom of the stub-shaft 20 in previous installations where the latter only was present, for the purpose, as already explained, of being turned in one direction or the other for winding up or lowering the awning.

Reverting to the shaft 49, for raising or lowering the drop-lid, when, by applying to the hook 75 a rod similar to the aforesaid long rod with a crank-like offset near its lower end, the stub-shaft 62 is rotated to turn the worm 60,

thereby through the worm-gear segment 59, to rock the said shaft 49, the latter may be of any length appropriate to the width of the swing-plate 48 and may be supported at its end remote from the bracket 68 in any convenient way, as by an additional bracket as indicated at 76.

Referring now more particularly to the auxiliary means incorporating the channel member 23 and the rocker member 24, note that the member 23 has its channel-mouth outwardly and downwardly directed, and that the width of said mouth is greater than the diameter of the rocker member 24 so that the rocker member can be engaged therethrough and into the channel of the member 23. A strip 77 of spring steel or aluminum alloy, is mounted on the channel member 23 partially closing its open mouth to retain the rocker member 24 in position in the channel member. The strip 77 is engaged along its bottom longitudinal marginal portion with the bottom horn 78 of the member 23, and along its top longitudinal marginal portion with a rib 78' extending longitudinally of the channel member 23 and projected therefrom toward the interior of the awning box.

Thus, in assembling the new means auxiliary to the hinge means, all that is required is to insert the member 24 into the member 23 as just explained, and then snap into place the strip 77.

The member 24 has, extending longitudinally thereof, an upper downwardly and inwardly directed horn 79, and, also extending longitudinally thereof, a rearwardly projected rib 80, while said member 24, at its outer side, has a rain-water shedding declivity 81 starting at its top about opposite the root of the rib 80 and ending at its bottom at the outer face of the section 28 of the drop-lid and well beyond the member 23 at its said channel-mouth. With the lid closed, the parts are arranged as shown in the drawing, but with the weight of the drop-lid carried wholly by the shaft 49. Such weight is always thus carried, too, while the drop-lid is raised, and while it is being raised or lowered. In raising the drop-lid, as the horn 79 leaves close adjacency to the upper limit of the channel-mouth, the rib 80 travels down opposite and in close adjacency to the upper surface of the horn 78; and in lowering the drop-lid, as the rib 80 travels beyond the upper surface of the horn 78 the horn 79 returns to close adjacency to the upper limit of the channel-mouth.

The new awning box, therefore, is well adapted to satisfy all the objects hereinabove first recited; and is characterized further by all the features and advantages elsewhere hereinabove pointed out.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections

having its top and bottom edges inserted into said grooves, a tie-plate extended across the inner faces of said sections, and means securing said sections to said tie-plate to hold said sections properly spaced and retain the top and bottom edges of said panel in said grooves.

2. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having a top groove, a panel between said sections having its top and bottom edges inserted into said

grooves, a tie-plate extended across the inner faces of said sections, and means securing said sections to said tie-plate to hold said sections properly spaced and retain the top and bottom edges of said panel in said grooves, said securing means comprising spaced rib formations on the inner faces of said sections forming channels, a clamp-bar in each of said channels, and means securing said tie-plates to said clamp-bars.

3. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said

grooves, a tie-plate extended across the inner faces of said sections, and means securing said sections to said tie-plate to hold said sections properly spaced and retain the top and bottom edges of said panel in said grooves, said securing means comprising spaced rib formations on the inner faces of said sections forming channels, a clamp-bar in each of said channels, and means securing said tie-plates to said clamp-bars.

3. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said

grooves, a tie-plate extended across the inner faces of said sections, and means securing said sections to said tie-plate to hold said sections properly spaced and retain the top and bottom edges of said panel in said grooves, said securing means comprising spaced rib formations on the inner faces of said sections forming channels, a clamp-bar in each of said channels, and means securing said tie-plates to said clamp-bars.

4. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said

grooves, a tie-plate extended across the inner faces of said sections, and means securing said sections to said tie-plate to hold said sections properly spaced and retain the top and bottom edges of said panel in said grooves, said securing means comprising spaced rib formations on the inner faces of said sections forming channels, a clamp-bar in each of said channels, and means securing said tie-plates to said clamp-bars, each of said rib formations including a main portion extending at right angles from its associated section and an angularly extending portion having an inner face facing the inner face of its associated section.

4. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said

grooves, a tie-plate extended across the inner faces of said sections, and means securing said sections to said tie-plate to hold said sections properly spaced and retain the top and bottom edges of said panel in said grooves, said securing means comprising spaced rib formations on the inner faces of said sections forming channels, a clamp-bar in each of said channels, and means securing said tie-plates to said clamp-bars, each of said rib formations including a main portion extending at right angles from its associated section and an angularly extending portion having an inner face facing the inner face of its associated section, said channels being substantially C-shaped in cross-section, said clamp-bars being wider than the mouth openings of said C-shaped

70 channels, serrations on the inner faces of the angularly extending portions of said rib formations, and complementary serrations on the adjacent faces of said clamp-bars and engaging said serrations.

5. In an awning box having an open front side

and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate extended across the inner faces of said sections, and means securing said sections to said tie-plate to hold said sections properly spaced and retain the top and bottom edges of said panel in said grooves, said securing means comprising spaced rib formations on the inner faces of said sections forming channels, a clamp-bar in each of said channels, and means securing said tie-plates to said clamp-bars, each of said rib formations including a main portion extending at right angles from its associated section and an angularly extending portion having an inner face facing the inner face of its associated section, said channel being substantially C-shaped in cross-section, said clamp-bars being wider than the mouth openings of said C-shaped channels, serrations on the inner faces of the angularly extending portions of said rib formations, and complementary serrations on the adjacent faces of said clamp-bars and engaging said serrations, said serrations and said complementary serrations being extended vertically.

6. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate extended across the inner faces of said sections, and means securing said sections to said tie-plate to hold said sections properly spaced and retain the top and bottom edges of said panel in said grooves, said securing means comprising spaced rib formations on the inner faces of said sections forming channels, a clamp-bar in each of said channels, and means securing said tie-plates to said clamp-bars, each of said rib formations including a main portion extending at right angles from its associated section and an angularly extending portion having an inner face facing the inner face of its associated section, said channels being substantially C-shaped in cross-section, said clamp-bars being wider than the mouth openings of said C-shaped channels, serrations on the inner faces of the angularly extending portions of said rib formations, and complementary serrations on the adjacent faces of said clamp-bars and engaging said serrations, said serrations and said complementary serrations being extended vertically, said securing means securing said tie-plate to said clamp-bars including threaded elements engaged through said tie-plate and said clamp-bars.

7. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate having elongated slots therein and extending across the inner faces of said sections, and means securing said sections to said tie-plate to hold said sections properly spaced and retain the top and bottom edges of

5 said panel in said grooves, said securing means comprising spaced rib formations on the inner faces of said sections forming channels, a clamp-bar in each of said channels, and means securing said tie-plates to said clamp-bars, each of said rib formations including a main portion extending at right angles from its associated section and an angularly extending portion having an inner face facing the inner face of its associated section, said channels being substantially C-shaped in cross-section, said clamp-bars being wider than the mouth openings of said C-shaped channels, serrations on the inner faces of the angularly extending portions of said rib formations, and complementary serrations on the adjacent faces of said clamp-bars and engaging said serrations, said serrations and said complementary serrations being extended vertically, said securing means securing said tie-plate to said clamp-bars including threaded elements engaged through said tie-plate and said clamp-bars, said threaded elements being extended through said elongated slots in said tie-plate and extended at right angles to the widths of said sections so that said sections can be spaced for the reception of panels of different widths therebetween.

8. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate extended across the inner faces of said sections, and means securing said sections to said tie-plate to hold said sections properly spaced and retain the top and bottom edges of said panel in said grooves, and manually operative means connected to said lower section for swinging the lid to an open position.

9. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate extended across the inner faces of said sections, and means securing said sections to said tie-plate to hold said sections properly spaced and retain the top and bottom edges of said panel in said grooves, said pivotal attaching means comprising a C-shaped channel member mounted on the top wall, and a rocker member on the top of said upper section and turnably engaged in said channel member.

10. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate extended across the inner faces of said sections, and means securing said sections to said tie-plate to hold said sections properly spaced and retain the top and bottom edges of said panel in said grooves, said pivotal attaching means comprising a C-shaped channel member mounted on the top wall, and a rocker member on the top of said upper section and

turnably engaged in said channel member, said rocker member being integrally formed on the top of said upper section.

11. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate extended across the inner faces of said sections, and means securing said sections to said tie-plate to hold said sections properly spaced and retain the top and bottom edges of said panel in said grooves, said pivotal attaching means comprising a C-shaped channel member mounted on the top wall, and a rocker member on the top of said upper section and turnably engaged in said channel member, said C-shaped channel member having its open side faced downwardly and slightly outwardly.

12. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate extended across the inner faces of said sections, and means securing said sections to said tie-plate to hold said sections properly spaced and retain the top and bottom edges of said panel in said grooves, said pivotal attaching means comprising a C-shaped channel member mounted on the top wall, and a rocker member on the top of said upper section and turnably engaged in said channel member, said C-shaped channel member having its open side faced downwardly and slightly outwardly, said open side of said C-shaped channel having a

width less than the diameter of said rocker member but greater than the thickness of the junction of said rocker member and said upper section where it passes through said open side permitting pivotal movement of the lid through a wide range.

13. In an awning box having an open front side and a top wall, a drop lid for closing the open front side, comprising an upper section having a bottom groove, means pivotally attaching the top of said upper section to the top wall at the top of the open front side, a lower section having a top groove, a panel between said sections having its top and bottom edges inserted into said grooves, a tie-plate extended across the inner faces of said sections, and means securing said sections to said tie-plate to hold said sections properly spaced and retain the top and bottom edges of said panel in said grooves, said pivotal attaching means comprising a C-shaped channel member mounted on the top wall, and a rocker member on the top of said upper section and turnably engaged in said channel member, said C-shaped channel member having its open side faced downwardly and slightly outwardly, said open side of said C-shaped channel having a width greater than the diameter of said rocker member so that said rocker member can be engaged into said C-shaped channel, and a strip mounted on said C-shaped channel for partially closing its open side for retaining said rocker element in said C-shaped channel.

ERROL P. D'AZZO.
